FURNACE GRATE

Charles F. Regan, New York, N. Y., assignor to
Caroline Regan, New York, N. Y.Application October 23, 1929, Serial No. 401,639
Renewed February 20, 1934

20 Claims. (Cl. 126—180)

My invention relates to improvements in furnaces and more particularly to furnace grates, and has for one of its objects to provide a furnace grate having a very low resistance to the passage 5 of air therethrough, so that sufficient air finds access to the fuel on the grate to insure complete combustion of such fuel and is distributed uniformly over the surface of the grate. It is also an object of the invention so to construct a furnace 10 grate that the same may easily and quickly be repaired by the attendant or householder without the need of expert help or of special parts. It is a further object of the invention to provide a grate which is composed of easily removable and 15 replaceable parts of simple construction which can be manufactured at a low cost. Other objects will appear from the description following and the features of novelty will be pointed out in the claims.

20 One of the most important considerations in the design and construction of a furnace grate is the insurance of a sufficient supply of fresh air for the fuel so as to obtain as complete and as uniform a combustion as possible. For efficient and 25 economical combustion, not only must provision be made for an abundant supply of air during the comparatively slow burning of the free carbon content of the fuel, which is generally anthracite coal, but a sufficient quantity of air must be present 30 to burn, at the surface of the fuel on the grate, the combustible vapors and gases which quickly escape when a new layer of coal is spread over the bed of incandescent coals on the grate. With known types of grates a large part of these 35 combustible gases and vapors escapes from the combustion space and is lost before enough oxygen can reach the same to support combustion thereof. This has been due largely to the fact that grates as heretofore constructed have usually been composed of a more or less flat plate of metal provided with slots for the passage of air, the area of the metal surface being generally greater than that of the slots, so that great resistance is encountered by the air. These slots have to be 40 made small to prevent the fuel from falling through the grate; at the same time, since the grate element is produced by casting, it is necessary to make the metal strips defining the slots rather wide, for if the metal lacework were made 45 thin and delicate, the pattern could not be removed from the sand in the mold without injuring the impression, while the molten metal on pouring would frequently solidify before filling all the fine passageways and on cooling strains would be 50 set up because of the difference in the rate of

cooling between the heavy mass of metal at the ends of the grate element and the thin lacework of metal intermediate such ends, so that defective castings would frequently result. For these reasons, known grates of this type are made with 60 comparatively large and continuous metallic surfaces between the air slots so that, as stated, great resistance is opposed to the flow of air and combustion is consequently incomplete. Other grates are known which are composed of a number of 65 separate elements designed to be arranged side by side upon a grate bar and locked thereto, and provided with spaced teeth between which flowed the air for supporting the combustion. The present invention relates to this latter type of grates. 70 As heretofore constructed, the teeth, spacing members, supporting grate bar, and other members forming part of or associated with the grate offered considerable resistance to the flow of air and prevented complete and uniform combustion. 75 In my copending application Serial No. 347,367, filed March 15, 1929, of which the present application is a continuation in part, I describe a novel form and arrangement of teeth for the grate elements whereby the resistance to the flow of air 80 is reduced. In the present application I shall describe, among other things, a novel form of grate element, grate bar, and grate frame whereby not only is the flow area for air still further increased and the air-resistance correspondingly 85 diminished, but the replacement of parts is facilitated and the cost of manufacture reduced, while at the same time the shaker mechanism for rocking or dumping the grates is simplified and rendered flexible in a manner to be explained here- 90 inafter.

My invention will best be understood by reference to the accompanying drawings which show by way of example a preferred form of the invention. In said drawings,

Fig. 1 is a plan view of a grate constructed in accordance with the present invention, and shows the grate bars in position on the grate frame and a number of the grate elements in position on the bars;

Fig. 2 is a side view of a completely assembled grate and illustrates the shaker mechanism therefor;

Fig. 3 is a front view of the mechanism shown in Fig. 2;

Fig. 4 shows an enlarged perspective of a grate bar;

Fig. 5 is a section along the line 5—5 of Fig. 6;

Fig. 6 illustrates an enlarged front view, partly

110

in section, of a grate bar with a number of the grate elements thereon; and

Figs. 7 and 8 illustrate two forms of grate elements forming part of a grate bar assembly.

5 My improved grate comprises a frame 10 having aligned pairs of sockets 11 designed to receive the trunnions 12 on grate bars 13, all as clearly shown in Fig. 1. The frame 10 is composed of two side members 14 connected at their ends by bars 15, the side members and end bars being connected in any suitable manner, as by means of a tapered tongue and groove connection 16. Upon each of the grate bars are mounted a plurality of grate elements 17, to be described more in detail hereinafter, only a small number of such elements being shown in position in Fig. 1. It will be understood that a number of assembled frames 10 may be arranged side by side within the combustion space of a furnace, the frames being mounted in any desired fashion upon a suitable foundation.

20 In accordance with the present invention the grate bars 13 are constructed in such a manner that they offer a minimum of resistance to flow of air upwardly through the grate and also provide for sufficient clearance between adjacent grate elements and grate bars when the latter are oscillated or rocked to dump the grate elements. As shown more in detail in Fig. 4, the bar 13 is composed of a pair of spaced longitudinal side members connected at their ends by the plates 18, such plates carrying the trunnions 12. The side members are connected only at their ends so that the interior of the bar is free of any obstruction for a purpose to be set forth hereinafter. It will be observed that the bar 13 is of extremely simple form, presents only a small mass of metal in the path of flow of the air, and can be easily manufactured at a low cost. The side members are preferably parallel to each other, as shown, but they may, if desired, be inclined to the vertical. The edges of the side members may be slightly beveled, as shown at 18' to reduce deformation as a result of expansion and contraction.

45 The bars 13 are each designed to support a plurality of removable grate elements 17 arranged in separate rows thereon. As shown in Fig. 8, each of the elements 17 comprises a segment-like portion 19 from which extends centrally thereof a stem of tongue portion 20. This tongue portion is preferably so dimensioned that it fits closely or snugly between the side members of the bar 13. In this manner the bar 13 is reinforced by the tongues of the grate elements 17 against distortion, and especially against inward bending of the side members of the bar. The grate elements are each provided with slots 21 adapted to receive the upper ends of the side members of the grate bar as the elements are lowered onto the bar, the walls of such slots cooperating with the bar to prevent more than slight transverse movement of the grate elements with respect to the bar. As will be clear from Figs. 4, 5, 6 and 8, the grate elements may easily be inserted upon or removed from the grate bar merely by lowering or raising the same vertically and without disturbing any of the other grate elements on such bar. A defective or burnt-out element can therefore be removed and replaced with very little effort and in a very short time. It will also be clear that the grate elements can readily be slid along the length of the bar as no obstruction is present to prevent such movement.

70 While each grate element is shown as provided

with two slots, a single slot may in certain cases be sufficient.

The upper edge of the grate elements, as shown in Fig. 8, is preferably made highly convex longitudinally of such elements, i. e. transversely of the grate bar, thereby increasing quite considerably the effective area of the grate. The upper edge of the grate elements is also rounded transversely of such elements as shown in Figs. 3 and 6 and as described in my above-mentioned application. Mounted upon each side of the grate elements and below the top edge thereof is an arcuate row of teeth 22. These teeth are spaced sufficiently close together to prevent coal of small size, such as buckwheat, from falling through, but are so designed as to afford a maximum of flow area for combustion supporting air. To this end the teeth are made of curved outline, at least at the upper portion thereof, and are preferably in the form of truncated cones with their larger bases next to the body of the grate elements. The opposing walls of adjacent teeth thus diverge at the upper portions of the teeth, thereby promoting distribution of air longitudinally of the grate elements, such air rising from below the teeth. The grate elements are adapted to be so positioned upon the grate bar that opposed sets of teeth upon adjacent elements are preferably in alignment and spaced from each other. This spacing is accomplished by means of lugs 23 integral with the grate elements and, like the teeth 22, built in the form of truncated cones. The lugs on each side of an element are spaced from each other; the lugs are also small in size, so that they offer very little resistance to the air.

40 As shown in Figs. 1, 3 and 6, the side members 14 of the frame 10 are curved so as to correspond with the outline of the rows of grate elements arranged between the same. The body of fuel may consequently extend to and upon the side members, so that the effective grate area is increased. In order to improve the circulation of air at such side members, I provide the latter with teeth which are similar to the teeth on the grate elements, and in order to bring the opposing series of teeth of the last or end grate elements on the grate bars close to the teeth on the grate frame, I omit the spacing lugs 23 from the outer face of such end grate elements (see Fig. 6). To insure a sufficient draft of air from the sides of the frame I provide the side members with air vents 24 adjacent to the upper surface thereof. The end bars 15 are similarly provided with air vents 25 as illustrated in Fig. 3.

55 As shown in Figs. 2, 3, 5, 6, and 7, at least one 130 of the grate elements on each of the bars 13 is provided with an extension 26 having an opening 27 through which it may be bolted to a shaker bar 28' operated in any suitable manner from the front of the furnace. This element is preferably the end element as shown in Fig. 6 and is in other respects similar to the elements 17. When it forms one of the end elements on a grate bar, it is provided with spacing lugs 23 at only the one side thereof. In order to prevent such end element 17 from working its way up through the bar 13 as the same is oscillated, the extension 26 is enlarged at its upper end to provide shoulders 28 which engage the underside of the bar 13. To facilitate insertion of the enlarged extension 26 through the bar 13, the latter is provided at its underside with slots 29 which are out of alignment with each other, as shown in Figs. 4 and 6. To position the end element 17 upon the bar 13 the former is inserted between the 140

70

145

150

side members of the latter in an askew manner as indicated in dotted lines in Fig. 1, so that the shoulders 28 engage the slots 29, whereupon the element may be turned until it is at right angles 5 to the bar and may then be slid to the end of the latter.

It will be seen that by the provision of an extension on one of the removable grate elements I dispense with the necessity of casting a shaker 10 arm integral with the grate bar 13. In this way I not only simplify the construction of the grate bar, but facilitate and reduce the cost of replacement should the shaker bar become damaged or broken; for should such arm be broken in known 15 constructions, wherein it forms an integral part of the grate bar, not only must the whole grate bar be replaced, but the whole assembly must be removed from the grate frame. In an apparatus constructed in accordance with the present in- 20 vention it is only necessary to remove and replace the end grate element 17 without in any way disturbing the grate bar or more than one or two of the grate elements 17. Such replacement can easily be done by a non-skilled attendant or 25 householder in a very short time.

A further advantage of that feature of my invention which involves the attaching of the shaker arm to one of the grate elements resides in the fact that where insufficient clearance exists at the end of the grate bar for the shaker mechanism, as for example, in circular furnaces, the special grate element 17 provided with the extension 26 may be moved inwardly upon the grate bar until sufficient clearance is provided, the 30 space on the bar between such element and the end of the bar being filled with the normal elements 17.

It will be clear from Figs. 4, 6, 7, and 8, that the grate bar and elements constructed in accordance with my invention present a minimum of obstruction to the flow of air through the grate, so much so that complete and uniform combustion can be obtained with a natural draft, the 40 gases and vapors escaping from a new charge of coal being completely burned at the surface of the grate. The grate elements, it will be noted, are composed for the greater part of a flat, comparatively thin, strip or web of metal while the spacer lugs 23, of which preferably three are provided on each side of the elements, except, of course, the end elements, are small and do not impede the flow of air. As a result a large volume of air reaches the teeth 22 which are spaced both from each other and from the opposing set 50 of teeth, so that the air encounters little resistance and gains ready access to the fuel on the grate. The construction of the parts is such that the air spreads in a fan-wise manner through the teeth 22 transversely of the grate bar because of the fact that they encounter no angular or sharp corners, such spreading being promoted by the flaring path afforded each stream 60 of air passing between adjacent teeth, as will be clear from Figs. 5, 7 and 8. Furthermore, because of the fact that the teeth taper outwardly while at the same time upper edges of the grate elements are curved as shown in Figs. 3 and 6 the air also finds a flaring or widening path longitudinally of the grate bars as it passes through 70 the grate teeth. As the teeth are dropped below the upper edges of the grate elements, considerable space is provided between the bed of coal on the grate and the teeth, the air circulating through such spaces. In this manner the air encounters a minimum of resistance and is dis-

tributed uniformly over the surface of the grate. The grate elements may be provided with vents 29 through which the air may course to cool the elements where they are hottest.

My improved grate can be easily installed in any type of furnace in a very short time and requires no brickling up or special foundation. The parts described above can be manufactured in any foundry and require no special apparatus.

In order to prevent binding of the grate bars against the sides of the frame as a result of expansion, I provide washers 12' at the ends of the bars, which are arranged to engage similar projecting washers upon the frame.

Variations may be resorted to within the scope of the appended claims without departing from the spirit of the invention.

I claim:

1. In a furnace grate, in combination, a grate bar of substantially rectangular cross-section and including two spaced substantially vertical side members, and a plurality of substantially T-shaped grate elements whose stem portions are adapted to fit snugly between said side members, whereby the latter are reinforced by said stem 100 portions against distortion inwardly, the horizontal portion of said T-shaped elements being provided with rectangular notches arranged to receive snugly the upper edges of the said side members as said elements are lowered onto the 105 grate bar, whereby said side members are reinforced against distortion outwardly by the outer walls of such notches, said grate elements resting only upon the upper surfaces of said side members and each being removable and re- 110 placeable by free vertical movement thereof with respect to the grate bar without disturbing the remaining elements.

2. The combination as set forth in claim 1 including an additional T-shaped grate element 115 having an extension on its stem for connection with an actuating member for rocking the grate bar.

3. In a furnace grate, in combination, a grate bar of substantially rectangular cross-section 120 and including two spaced substantially vertical side members, a plurality of substantially T-shaped grate elements whose stem portions are adapted to fit snugly between said side members, whereby the latter are reinforced by said 125 stem portions against distortion inwardly, the horizontal portion of said T-shaped elements being provided with rectangular notches arranged to receive snugly the upper edges of the said side members as said elements are lowered 130 onto the grate bar, whereby said side members are reinforced against distortion outwardly by the outer walls of such notches, said grate elements resting only upon the upper surfaces of said side members and each being removable 135 and replaceable by free vertical movement thereof with respect to the grate bar without disturbing the remaining elements, and spaced cone-shaped spacing lugs on each of said grate elements adapted to engage similar lugs on an adjacent element for holding such elements in spaced relation to afford a substantially unobstructed passage for air between said elements.

4. In a furnace grate, in combination, a grate bar comprising a pair of spaced side members, 145 and a plurality of substantially T-shaped grate elements whose stems fit snugly between said side members and operate to reinforce the latter against distortion inwardly, said elements resting upon the upper surfaces of said side members 150

- and each being individually removable from the bar by lifting the same without disturbing the other elements, and a row of spaced, conical, fuel-supporting teeth at each side of each of said 5 elements vertically spaced from the uppermost edge thereof.
5. In combination, a grate bar comprising a pair of spaced side members, and a grate element having an intermediate portion of such width as 10 to fit snugly between the said members and having an enlarged bottom portion adapted to be connected to a shaker bar, said members being provided with notches at their lower edges, said notches being out of alinement, whereby said 15 element may be inserted obliquely between the side members of the bar and then be turned so as to cause the enlarged portion thereof to enter said notches to permit the said element to be positioned at right angles to such bar.
6. In a furnace grate, in combination, a grate bar comprising a pair of spaced side members of 20 rectangular cross-section, a plurality of grate elements resting on said bar, and each being individually removable from the bar by lifting the element, while the other elements are in position 25 on the bar, without disturbing such other elements, and spaced teeth in the vicinity of the upper edge of each element, each element being provided with rectangular slots arranged to receive snugly the said side members, whereby said 30 bar is reinforced against outward distortion by the outer walls of such notches.
7. The combination as set forth in claim 1 wherein said grate bar is free of transverse webs 35 intermediate its ends, whereby the grate elements resting on the bar can be shifted therealong.
8. In a furnace grate, in combination, a grate bar comprising a pair of spaced side members, a plurality of grate elements resting on said bar 40 and capable of movement longitudinally of said bar while in position thereon, each of said elements being individually removable from and replaceable on such bar while the remaining elements are in place without disturbing such remaining elements, spaced teeth in the vicinity of 45 the upper edge of each element, and means for rocking said bar parallel to the planes of said elements, said teeth being in the form of a truncated cone.
9. In a furnace grate, in combination, a grate 50 bar consisting of only two spaced vertical side members which are smooth upon their inner faces, the bar being free of transverse webs intermediate its ends, and a plurality of substantially T-shaped grate elements whose stem portions have parallel vertical edges and are of such width 55 as to fit snugly between the vertical side members of the grate bar, grate teeth on said elements, and spacing lugs on said elements, said elements being placeable on and removable from said side members merely by free vertical movement, and said teeth being of curved outline in planes parallel 60 to the said elements and being disposed below the top edges of said elements, whereby resistance to the passage of air is reduced and spreading of such air longitudinally of said elements is promoted.
10. In a furnace grate, in combination, a grate 65 bar comprising a pair of spaced side members, and a plurality of substantially T-shaped grate elements whose stems fit snugly between said side members and operate to reinforce the latter against distortion inwardly, said elements resting upon the upper surfaces of said side members and each being individually removable from the bar 70 by lifting the same while the other elements are in position on the bar, without disturbing such other elements, each of said elements having on each side thereof a row of spaced, fuel-supporting teeth which are curved at the upper portions 80 thereof and are arranged below the uppermost edges of said elements a sufficient distance to enable air travelling upwardly between the elements and between the teeth to flow over the curved surfaces of such teeth through the space 85 between such teeth and the top edges of the elements and become distributed along the length of such elements below the bed of fuel resting on the latter.
11. In a furnace grate, in combination, a grate 90 bar of substantially rectangular cross-section and including two spaced substantially vertical side members, and a plurality of substantially T-shaped grate elements whose stem portions are adapted to fit between said side members, whereby the latter are reinforced by said stem portions against distortion inwardly, the horizontal portion of said T-shaped elements being provided with rectangular notches, which receive said 95 members, the outer walls of said notches snugly engaging said members so that such horizontal portions reinforce the members against distortion outwardly, spaced teeth on said grate elements, said spaced side members and spaced teeth affording a passageway of large area for air passing 100 upwardly between the grate elements, said elements having each an aperture therein near the top thereof to permit the air to travel transversely of the elements to cool the latter.
12. In a furnace grate, in combination, a rack 105 member, a plurality of grate units mounted on said member, and grate teeth on each of said units, at least the upper portions of said teeth being of curved outline, longitudinally of such units, whereby corners are eliminated at the upper portions of said teeth and the opposing walls of adjacent teeth diverge at the top portions of 115 said teeth so that air flowing upwardly between the teeth spreads over the length of said units, the upper surfaces of said elements being convexly curved in planes transverse to the length of the rack member.
13. In a furnace grate, in combination, a grate 120 bar, a plurality of grate elements removably mounted on said bar, and grate teeth on said 125 elements below the top surface of said elements, said teeth being of the form of a truncated cone, whereby corners are eliminated and resistance to the passage of air reduced.
14. In a furnace grate, in combination, a grate 130 bar, a plurality of grate elements removably mounted on said bar, and grate teeth on said elements below the top surface of said elements, the top surface of said elements being curved transversely thereof and said teeth being of curved 135 outline, whereby corners are eliminated and resistance to the passage of air reduced.
15. In a furnace grate, in combination, a grate 140 bar, a plurality of grate elements removably mounted on said bar, and grate teeth on said 145 elements below the top surface of said elements, the top surface of said elements being curved transversely thereof and said teeth being of the form of a truncated cone, whereby corners are eliminated and resistance to the passage of air reduced.
16. In a furnace grate, in combination, a grate 150 bar, a plurality of grate elements removably mounted on said bar, and grate teeth on said elements below the top surface of said elements,

- the top surface of said elements being curved transversely and longitudinally thereof and said teeth being of the form of a truncated cone, whereby corners are eliminated and resistance 5 to the passage of air reduced.
17. A removable grate element comprising a web member, and a row of spaced teeth upon each side of said member, said teeth being tapered transversely of the web member and of substantially circular vertical cross-section, and said rows of teeth being spaced from the top edge of said member to such an extent as to induce currents of air passing upwardly between the teeth to spread longitudinally of said web member and over the top edge thereof.
18. In a furnace grate, in combination, a grate bar, and a plurality of grate elements removably mounted on said bar, certain of said elements comprising a web member and a row of spaced teeth upon each side thereof, said teeth being tapered transversely of the web member and of substantially circular vertical cross-section, and said rows of teeth being spaced from the top edge of said web member to such an extent as to induce currents of air passing upwardly between the teeth to spread transversely of said web member and over the top edge thereof.
19. In a furnace grate, in combination, a grate bar, a plurality of grate elements mounted on said bar, and grate teeth on each of said elements, at least the upper portions of said teeth being of curved outline longitudinally of such elements, whereby corners are eliminated at the upper portions of said teeth and the opposing walls of adjacent teeth diverge at the top portions of said teeth so that air flowing upwardly between the teeth spreads over the length of said elements. 80
20. In a furnace grate, in combination, a grate bar, a plurality of grate elements removably mounted on said bar, and grate teeth on said elements, at least the upper portions of said teeth being of curved outline longitudinally of such elements, whereby corners are eliminated at the upper portions of said teeth and the opposing walls of adjacent teeth diverge at the top portions of said teeth, so that air flowing upwardly between the teeth spreads over the length of said elements, said teeth being dropped below the top edges of said elements a sufficient distance to provide passage for such air beneath a bed of coal on said elements. 85 90 95 100
